INDIVIDUAL ALARM WATCH

Solomon Axelrod, New York, N. Y., assignor of
one-third to Irving Bialer, New York, N. Y., and
one-third to Max Ember, Brooklyn, N. Y.

Application March 6, 1939, Serial No. 260,808

7 Claims. (CL. 58—16)

This invention relates to new and useful improvements in an individual alarm watch.

More specifically, the invention proposes the construction of an individual alarm watch characterized by a casing having a watch face and rotatively supporting a frame which supports a watch crystal having the setting mechanism of the alarm connected therewith in a manner to permit the alarm to be set for a desired predetermined time by the rotation of said crystal frame.

Still further the invention proposes the provision of an alarm mechanism characterized by an alarm control stem associated with the watch mechanism proper and having a cam mounted thereon and adapted to be rotated by the said watch mechanism for controlling the operation of said alarm.

Another object of the invention is the provision of an alarm mechanism characterized by a telescopic stem or stem with a ring for winding the alarm spring and for engaging against one's skin when the alarm is set off for notifying a person of the same.

Still further it is proposed to provide a catch mounted on an operator rod connected with the cam of said alarm system for holding the stem in its retracted position and for permitting the stem to be extended when said alarm goes off.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevational view of an individual alarm watch constructed according to this invention.

Fig. 2 is a rear elevational view of Fig. 1.

Fig. 3 is a sectional view substantially on the line 3—3 of Fig. 1.

Fig. 4 is a sectional view substantially on the line 4—4 of Fig. 3.

Fig. 5 is a view looking in the direction of the line 5—5 of Fig. 3.

Fig. 6 is a sectional view on the line 6—6 of Fig. 3.

Fig. 7 is a view looking in the direction of the line 7—7 of Fig. 3.

Fig. 8 is an enlarged detailed view of a portion of Fig. 3 but illustrating the telescopic stem in its extended position.

Fig. 9 is an enlarged detailed view of a portion of Fig. 4.

Fig. 10 is a sectional view on the line 10—10 of Fig. 7.

Fig. 11 is a fragmentary perspective bottom view illustrating a portion of an individual alarm watch constructed according to a modification of this invention.

The individual alarm watch, according to this invention, comprises a casing 10 having outwardly extending lugs 10^a on diametrically opposite sides thereof. Wrist straps 11 are adapted to be engaged upon the lugs 10^a for holding the watch case 10 in position upon one's wrist. The watch case 10 is characterized by an inner section 10^a and an outer section 10^b having an open front side 10^bb. The side walls of the section 10^b encase the sides of the section 10^a. A pair of spaced plates 12 are mounted within the casing 10 and the plate 12 adjacent the open end of the casing 10 supports a watch face 13 upon which advertising or other material is imprinted. This advertising matter may be frictionally held by suitable clips 13^a which are secured to the watch face 13 in a radial direction. In place of an advertisement, the spring clips may hold small objects such as a calendar, a picture and an identification card, a slogan or the like, or the watch face may be a mirror.

A watch crystal 14 is mounted in a frame 14^a 30 rotatively supported across the open side of the casing 10. The edges of the frame 14^a rest upon the upper end of the section 10^b and a ring 15 is engaged over the edge of the frame 14^a and is maintained in position by several screws 15^a for 35 permitting the frame 14^a and crystal 14 to be turned for controlling the alarm mechanism as hereinafter further described.

A tube 16 is rotatively extended through the top plate 12 and the watch face 13 and supports an hour hand 17 which is adapted to register with watch face numerals imprinted on the front face of the ring 15. A second tube 18 is rotatively extended through the tube 16 and has its inner end extended beyond the inner end of the tube 16 (see Fig. 3). The outer end of the tube 18 extends beyond the top face of the hour hand 17 and carries a minute hand 19 which is also adapted to register with the numerals imprinted on the ring 15.

A watch movement is provided for operating the hands 17 and 19. This watch movement is characterized by a shaft 20 rotatively supported and which carries a main spring casing 21. The main spring casing 21 is rotatively supported 55

upon the shaft 20 which rotation is limited by the wound condition of the spring contained therein. A ratchet wheel 22 is mounted upon the shaft 20 and is engageable by a pawl 23 mounted upon a portion of the main spring casing 21 for permitting the shaft 20 to be rotated independently of the casing 21 to cause the spring 24 located within the casing to be wound upon the shaft 20. The periphery of the main spring casing 21 is formed with gear teeth 21a which mesh at one side with an escapement mechanism 25, not completely shown on the drawings as it forms no part of the invention, and which controls the unwinding of the spring 24. The gear teeth 21a further mesh with a pinion 26 mounted on the inner end of the tube 16 carrying the hour hand 17 for causing the hour hand to make one complete revolution around the watch face 13 during a period of twelve hours.

20 A means is provided for causing the minute hand 19 to make twelve complete revolutions around the watch face for every twelve hour period. This means comprises a large gear 27 which meshes with the gear 26. The gear 27 is rotatively supported between the arms of a U-shaped bracket 28 mounted upon the inner face of the top plate 12. A shaft 29 is rotatively supported between the plates 12. A small pinion 30 is mounted upon the shaft 29 and meshes with the large gear 27 causing the shaft 29 to be rotated. A second large gear 31 is mounted upon the shaft 29 below the small pinion 30 and is adapted to rotate with the shaft 29 as it rotates. Still another shaft 32 is rotatively supported between the plates 12 and carries a pinion 33 which meshes with the large gear 31 for causing the shaft 32 to be rotated. Another gear 34 is mounted upon the shaft 32 below the gear 33 and meshes with a pinion 35 mounted upon the inner end of the tube 18 for causing the tube 18 to be rotated. The ratio of the gears is such that the gear 35 will rotate through twelve complete revolutions each time the gear 26 makes one complete revolution.

45 A means is provided for causing the spring 24 contained within the main spring casing 21 to be wound and for permitting the hands 17 and 19 to be correctly set for indicating the time. This means comprises a bevel gear 36 mounted upon the shaft 20 intermediate of its ends and which meshes with a bevel gear 37 fixedly mounted upon a shaft 38 which extends at right angles to the shaft 20. The shaft 38 is rotatively supported in a pair of bearings 39 contained within the casing. A large gear 40 is mounted upon the shaft 38 and meshes with a gear 41 mounted on a winding stem 42 which extends to the exterior of the casing and which is provided with a knob 43. The stem 42 is rotatively and slidably supported within a pair of bearings 44 contained within the casing 10.

65 When the gears 40 and 41 are meshing and the knob 43 is rotated in the proper direction for causing the stem 42 to rotate, the shaft 20 will be similarly rotated causing the spring 24 to be wound upon the shaft 20 while the main spring casing remains stationary. A means is also associated with the winding stem 42 for permitting the hands 17 and 19 to be adjusted for indicating the correct time. This means comprises a bevel gear 45 mounted upon the shaft 32 and which meshes with a bevel gear 46 mounted on the shaft 47 which extends at right angles to the shaft 32 and parallel with the shaft 38. The shaft 47 is rotatively supported in a pair of brackets 48 con-

tained within the watch casing 10. A gear 49 is mounted on the shaft 47 and is adapted to be engaged by the gear 41 in a pulled out position of the winding stem 42, as indicated by the dot and dash lines 42' in Fig. 9, for permitting the shaft 47 to be rotated to correspondingly rotate the shaft 32 and cause the hands to be adjusted independently of the main spring casing 21.

A means is provided for limiting the movement of the winding stem 42 to positions in which the gear 41 will mesh with either the gear 40 or the gear 49. This means comprises a collar 50 mounted on an intermediate portion of the winding stem 42 and which is provided with a pair of spaced grooves 50a. The grooves 50a are spaced from each other a distance equal to the space between the adjacent faces of the gears 40 and 49. A means is engageable into one or the other of the grooves for maintaining the stem 42 in a position in which the gear 41 meshes with the gear 40 or the gear 49. This means comprises a casing 51 mounted upon a bracket 52 adjacent the collar 50. A knob 53 extends from one end of the casing 51 adjacent the collar 50 and engages into one of the grooves 50a. A spring 54 operates between the inner end of the knob 53 and the other end of the casing 51 for urging the knob 53 into an extended position. When the knob engages the outermost groove 50a the gear 41 will mesh with the gear 40. However, when the winding stem 42 is pulled outwards, as indicated by the dot and dash line 42' in Fig. 9, the knob 53 will engage the innermost groove 50a and the gear 41 will mesh with the gear 49.

An alarm control stem 55 has its inner end rotatively supported upon the bottom plate 12 and extended through the innermost tube 18. The outer end of the alarm control stem 55 is fixedly attached to an alarm indicating hand 14b connected with the frame 14a for causing the control stem 55 to rotate therewith when the crystal frame is rotated. A pointer 56 extends from the frame 14a at a point 56a and is adapted to register with the numerals on the ring 15 for enabling the alarm mechanism to be set at a predetermined time for setting the alarm in operation. Both the indicating hand 14b and the pointer 56 are connected to the frame 14a at the point 56a.

A gear 57 is mounted on an intermediate portion of the control stem 55 and has a hub formed with a cam cutout 57a. The control stem carries a pin 58 which is aligned with the indicator pointer 56. A means is provided for urging the gear 57 to cause its hub to bear against the pin 58. This means comprises a collar 59 mounted on the control stem 55 below the gear 57. A strong spring 60 operates between the adjacent faces of the gear 57 and the collar 59 for causing the gear 57 to move towards the pointer 56 when the cam 57a is aligned therewith.

A means is provided for causing the gear 57 to be rotated through one complete revolution during a period of twelve hours for causing the alarm to be set in operation when the hour hand 17 reaches the predetermined time indicated by the indicator pointer 56. This means comprises a gear 61 mounted upon the shaft 32 below the gear 34 and which meshes with the gear 57 for causing the same to be rotated independent of the control stem 55.

An alarm spring casing 62 is fixedly mounted upon a bracket 63 mounted upon the bottom plate 12 and spaced from the gear 57. A telescopic winding stem 64 for the alarm mechanism ex-

tends from the interior of the alarm spring casing 62 to the exterior of the easing 10. The outer end of the alarm spring stem 64 is provided with a knob 65 normally contained within a recess 10c formed in the back face of the watch casing 10. When the knob 65 is rotated the spring contained within the alarm spring casing 62 will be tightly wound on the telescopic stem 64. A means is provided for preventing the spring from again unwinding until the pin 58 engages the cam cutout 57a, freeing the cam. This means comprises a ratchet wheel 66 mounted upon one end of the telescopic stem 64. An operator rod 67 has one of its ends rotatively engaged upon the hub of the gear 57 (see Fig. 18). The other of its ends is provided with a pin 68 which is adapted to engage the teeth of the ratchet wheel 66 for holding the stem 64 against rotating until such time as the gear 57 moves forward on the control stem 55 for disengaging the pin 68 from the teeth of the ratchet wheel 66. When this pin is disengaged from the teeth the spring quickly unwinds and the end of the telescopic stem 64 which bears against one's wrist rotates therewith indicating that the hour hand 17 has reached the predetermined time indicated by the pointer 56 and that the alarm has gone off.

The stem 64 is composed of separate sections consisting of a section 64a rotatively but non-slidably supported upon the alarm spring casing 62. A section 64b slidably but non-rotatively engages the end of the section 64a and is provided with the knob 65. A catch 70 is attached to the lower side of the operator rod 67 and normally engages a flange 64bb for holding the section 64b in position in which the knob 65 will be located within the recess 10c formed in the watch casing 10 (see Fig. 3). A portion of the catch 70 slidably engages through a bracket 71 supported on the back plate 12 for holding the operator arm 67 against rotating with the gear 57. When the cam cutout 57a is aligned with the pin 58 and the gear 57 is moved forwards by the action of the spring 60 the catch 70 will be disengaged from the flange 64bb and a means is provided for urging the section 64b into its extended position for more rigidly bearing against one's wrist.

The means for projecting the section 64b into its extended position comprises a collar 72 mounted upon the section 64a. A spring 73 is coaxially mounted upon the section 64a and operates between the adjacent face of the collar 72 and the inner end of the section 64b for urging the section 64b into its extended position when the catch 70 is disengaged therefrom. A collar 74 is mounted upon an intermediate portion of the section 64b and is adapted to strike the inner face of the projection 10c for preventing the section 64b from being completely disengaged from the section 64a when the catch 70 is disengaged therefrom.

A means is provided for slidably but non-rotatively connecting the section 64b with the section 64a. This means comprises a key 75 mounted within the opening in the section 64b into which the end of the section 64a extends and which engages a groove 76 formed in the section 64a. The key 75 is arranged radially of the stem 64.

The ring 15 has raised symbols 15b simulating the hour indications of the watch and which are adapted to be felt in the dark so that said alarm mechanism may be set at a predetermined desired time without light.

In the modified form of the invention illustrat-

ed in Fig. 11 the individual alarm watch is provided with an alarm winding stem 64' having a head 65' located within a recess 10c in the casing of the watch, and a ring 65'' is hingedly mounted on the head 65' and is adapted to be manually extended as shown by the full lines in Fig. 11, or to be folded back as indicated by the dot and dash lines. With this arrangement it is possible to wind the alarm by extending the ring 65'' and then applying rotations. In other respects this form of the invention is similar to the previous form.

The operation of this device is as follows:

The watch crystal frame 14a is rotated about the face of the casing 10 by engaging one's finger 15 nail against the pointer 56 which is integral with the crystal frame 14a and is formed with the groove or notch 56a and this notch 56a in turn is being engaged by the alarm indicating hand 14b, so as to cause the pointer 56 to be aligned with the predetermined numeral on the watch face ring 15 at which time it is desired to have the alarm mechanism go off. For setting the alarm mechanism the section 64b of the alarm 64 is pulled manually outwards for permitting the knob 65 to be rotated for tightly winding the stem of the spring mechanism 62 tightly upon the stem 64. The stem section 64b is manually urged inwards for engaging the flange 64bb with the catch 70 and the watch is engaged upon one's wrist. When the cam cutout 57a reaches an aligned position with the pin 58 the spring 60 will urge the gear 57 upward disengaging the pin 68 of the operator rod from the teeth of the ratchet wheel 66 freeing the winding stem 64. The movement of the operator rod 67 will simultaneously disengage the catch 70 from the flange 64bb freeing the stem section 64b permitting the spring 73 to urge the said section into its extended position for rigidly bearing against one's wrist for indicating that the alarm has gone off.

The individual alarm watch has an additional use, that of telling time in the dark, or by blind people who will be able to feel the setting of the alarm mechanism. This may be accomplished by moving, which is in the form of an arrow, across the ring 15 so as to change the time at which the alarm is set and moving the pointer until a position is reached in which the alarm operates. This will indicate the time. Then one need only feel the raised indications 15b to figure out the time. After this operation the pointer 56 may be again reset to set the ringing mechanism at a predetermined time.

A suitable stopper arrangement may also be provided to stop the alarm mechanism.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An individual alarm watch, comprising a watch face, a casing enclosing said watch face, an hour and a minute hand rotatively mounted to move across said watch face, a watch movement mounted in said casing for operating said hands, an alarm mechanism, a manually rotative alarm control stem adapted to be set to cause said alarm mechanism to operate at a predeter-

mined desired time, a pin projecting from one side of said control arm, a gear freely mounted on said control stem and having its hub abutting said pin and connected with said movement to be rotated thereby and synchronized with said hour hand to make one complete revolution in twelve hours, a cam cutout formed on the hub of said gear and in a superimposed aligned position with said hour hand to cause said cam cutout and pin to be aligned when said hour hand reaches the predetermined time at which said control stem has been set, resilient means on said control stem for urging the hub of said gear into contact with said pin and for urging said gear forward to cause said pin to engage into said cam cutout when said pin and cam cutout are aligned, a telescopic stem for winding said alarm mechanism and adapted to engage one's skin, an operator rod connected with said gear, a pin extending from said rod and engaging a complementary part of said alarm mechanism for normally holding said alarm mechanism inoperative and being disengageable from said part for releasing said alarm mechanism when said gear moves towards said first mentioned pin, a catch mounted on said operator rod for holding said telescopic stem retracted and for releasing said telescopic stem, and means for extending said telescopic stem in its released condition to engage one's skin when said alarm mechanism is released to indicate that the predetermined desired time has been reached.

2. An individual alarm watch, comprising a watch face, a casing enclosing said watch face, an hour and a minute hand rotatively mounted to move across said watch face, a watch movement mounted in said casing for operating said hands, an alarm mechanism, a manually rotative alarm control stem adapted to be set to cause said alarm mechanism to operate at a predetermined desired time, a pin projecting from one side of said control stem, a gear freely mounted on said control stem and having its hub abutting said pin and connected with said movement to be rotated thereby and synchronized with said hour hand to make one complete revolution in twelve hours, a cam cutout formed on the hub of said gear and in a superimposed aligned position with said hour hand to cause said cam cutout and pin to be aligned when said hour hand reaches the predetermined time at which said control stem has been set, resilient means on said control stem for urging the hub of said gear into contact with said pin and for urging said gear forward to cause said pin to engage into said cam cutout when said pin and cam cutout are aligned, a telescopic stem for winding said alarm mechanism and adapted to engage one's skin, an operator rod connected with said gear, a pin extending from said rod and engaging a complementary part of said alarm mechanism for normally holding said alarm mechanism inoperative and being disengageable from said part for releasing said alarm mechanism when said gear moves towards said first mentioned pin, a catch mounted on said operator rod for holding said telescopic stem retracted and for releasing said telescopic stem, and means for extending said telescopic stem in its released condition to engage one's skin when said alarm mechanism is released to indicate that the predetermined desired time has been reached, a frame carrying a watch crystal and rotatively supported by said casing coaxially of said control stem, an alarm hand in a superimposed position with relation to

said pin on said control stem and having one of its ends attached to the extended end of said control stem and its other end attached to a peripheral point on said frame, raised hour inscriptions formed on a stationary portion of said casing, and an indicating pointer in the form of an arrow extending from said peripheral point and overhanging said inscriptions so that blind people or persons in a dark room may set said alarm mechanism to operate at a predetermined desired time by feeling said inscriptions and aligning said indicating pointer with desired hour inscription. 5

3. An individual alarm watch, comprising a watch face, a casing enclosing said watch face, 15 an hour and a minute hand rotatively mounted to move across said watch face, a watch movement mounted in said casing for operating said hands, an alarm mechanism, a manually rotative alarm control stem adapted to be set to cause 20 said alarm mechanism to operate at a predetermined desired time, a pin projecting from one side of said control stem, a gear freely mounted on said control stem and having its hub abutting said pin and connected with said movement to 25 be rotated thereby and synchronized with said hour hand to make one complete revolution in twelve hours, a cam cutout formed on the hub of said gear and in a superimposed aligned position with said hour hand to cause said cam cutout and pin to be aligned when said hour hand reaches the predetermined time at which said control stem has been set, resilient means on 30 said control stem for urging the hub of said gear into contact with said pin and for urging said gear forward to cause said pin to engage into said cam cutout when said pin and cam cutout are aligned, a telescopic stem for winding said alarm mechanism and adapted to engage one's skin, an operator rod connected with said gear, 40 a pin extending from said rod and engaging a complementary part of said alarm mechanism for normally holding said alarm mechanism inoperative and being disengageable from said part for releasing said alarm mechanism when said 45 gear moves towards said first mentioned pin, a catch mounted on said operator rod for holding said telescopic stem retracted and for releasing said telescopic stem, and means for extending said telescopic stem in its released condition to 50 engage one's skin when said alarm mechanism is released to indicate that the predetermined desired time has been reached, a frame carrying a watch crystal and rotatively supported by said casing coaxially of said control stem, and alarm 55 hand in a superimposed position with relation to said pin on said control stem and having one of its ends attached to the extended end of said control stem and its other end attached to a peripheral point on said frame, raised hour inscriptions formed on a stationary portion of said casing, and an indicating pointer in the form of an arrow extending from said peripheral point and overhanging said inscriptions so that blind 60 people or persons in a dark room may set said alarm mechanism to operate at a predetermined desired time by feeling said inscription and aligning said indicating pointer with desired hour inscription, said pin and said alarm hand being aligned for causing said pin to assume the 65 same adjusted position with relation to said hour inscriptions as said indicating pointer. 70

4. An individual alarm watch, comprising a watch face, a casing enclosing said watch face, an hour and a minute hand rotatively mounted

- to move across said watch face, a watch movement mounted in said casing for operating said hands, an alarm mechanism, a manually rotative alarm control stem adapted to be set to cause said alarm mechanism to operate at a predetermined desired time, a pin projecting from one side of said control stem, a gear freely mounted on said control stem and having its hub abutting said pin and connected with said movement to be rotated thereby and synchronized with said hour hand to make one complete revolution in twelve hours, a cam cutout formed on the hub of said gear and in a superimposed aligned position with said hour hand to cause said cam cutout and pin to be aligned when said hour hand reaches the predetermined time at which said control stem has been set, resilient means on said control stem for urging the hub of said gear into contact with said pin and for urging said gear forward to cause said pin to engage into said cam cutout when said pin and cam cutout are aligned, a telescopic stem for winding said alarm mechanism and adapted to engage one's skin, an operator rod connected with said gear for normally holding said alarm mechanism inoperative and for releasing said alarm mechanism when said gear moves towards said pin, a catch mounted on said operator rod for holding said telescopic stem retracted and for releasing said telescopic stem, and means for extending said telescopic stem in its released condition to engage one's skin when said alarm mechanism is released to indicate that the predetermined desired time has been reached, said operator rod being rotatively connected with said gear, a bracket for axially slidably supporting said operator rod, a ratchet wheel mounted on said alarm mechanism, and a pin extending from said operator rod and engaging said ratchet wheel to hold said alarm mechanism inoperative.
5. An individual alarm watch, comprising a watch face, a casing enclosing said watch face, an hour and a minute hand rotatively mounted to move across said watch face, a watch movement mounted in said casing for operating said hands, an alarm mechanism, a manually rotative alarm control stem adapted to be set to cause said alarm mechanism to operate at a predetermined desired time, a pin projecting from one side of said control stem, a gear freely mounted on said control stem and having its hub abutting said pin and connected with said movement to be rotated thereby and synchronized with said hour hand to make one complete revolution in twelve hours, a cam cutout formed on the hub of said gear and in a superimposed aligned position with said hour hand to cause said cam cutout and pin to be aligned when said hour hand reaches the predetermined time at which said control stem has been set, resilient means on said control stem for urging the hub of said gear into contact with said pin and for urging said gear forward to cause said pin to engage into said cam cutout when said pin and cam cutout are aligned, a telescopic stem for winding said alarm mechanism and adapted to engage one's skin, an operator rod connected with said gear, a pin extending from said rod and engaging a complementary part of said alarm mechanism for normally holding said alarm mechanism inoperative and being disengageable from said part for releasing said alarm mechanism when said gear moves towards said first mentioned pin, and a catch mounted on said operator rod for holding said telescopic stem retracted and for releasing said telescopic stem to engage one's skin when said alarm mechanism is released to indicate that the predetermined desired time has been reached, said telescopic stem being formed of separate sections slidably but non-rotatively connected together, and means for causing one of said sections to be extended to engage one's skin when said catch disengages therefrom, comprising a collar mounted on one of said sections, a spring coaxially mounted on said section carrying said collar and operating between said collar and the other of said sections.
7. An individual alarm watch, comprising a watch face, a casing enclosing said watch face, an hour and a minute hand rotatively mounted to move across said watch face, a watch movement mounted in said casing for operating said hands, an alarm mechanism, a manually rotative alarm control stem adapted to be set to cause said alarm mechanism to operate at a predetermined desired time, a pin projecting from one side of said control stem, a gear freely mounted on said control stem and having its hub abutting said pin and connected with said movement to be rotated thereby and synchronized with said hour hand to make one complete revolution in twelve hours, a cam cutout formed on the hub of said gear and in a superimposed aligned position with said hour hand to cause said cam cutout and pin to be aligned when said hour hand reaches the predetermined time at which said control stem has been set, resilient means on said control stem for urging the hub of said gear into contact with said pin and for urging said gear forward to engage one's skin when said alarm mechanism is released from said part for releasing said alarm mechanism when said gear moves towards said first mentioned pin, a catch mounted on said operator rod for holding said telescopic stem retracted and for releasing said telescopic stem to engage one's skin when said alarm mechanism is released to indicate that the predetermined desired time has been reached, said telescopic stem being formed of separate sections slidably but non-rotatively connected together, and means for causing one of said sections to be extended to engage one's skin when said catch disengages therefrom, comprising a collar mounted on one of said sections, a spring coaxially mounted on said section carrying said collar and operating between said collar and the other of said sections.

ward to cause said pin to engage into said cam cutout when said pin and cam cutout are aligned, a telescopic stem for winding said alarm mechanism and adapted to engage one's skin, an operator rod connected with said gear, a pin extending from said rod and engaging a complementary part of said alarm mechanism for normally holding said alarm mechanism inoperative and being disengageable from said part for releasing said alarm mechanism when said gear moves towards said first mentioned pin, a catch mounted on said operator rod for holding said telescopic stem retracted and for releasing said telescopic stem to engage one's skin when said alarm mechanism is released to indicate that the

predetermined desired time has been reached, said telescopic stem being formed of separate sections slidably but non-rotatively connected together, and means for causing said section engaged by said catch to be extended to engage one's skin when said catch disengages therefrom, comprising a collar mounted on one of said sections, a spring coaxially mounted on said section carrying said collar and operating between said collar and the other of said sections, and a knob formed on said stem and adapted to be manually grasped and rotated in the extended position of said stem for causing the spring of said alarm mechanism to be wound.

SOLOMON AXELROD. 15
